UNITED STATES PATENT OFFICE.

LEWIS H. LANIER, OF NEWPORT, KENTUCKY, ASSIGNOR OF ONE-HALF TO L. L. STRICKER, OF CINCINNATI, OHIO.

ICE-CREAM-CONE OVEN.

964,873.

Specification of Letters Patent. Patented July 19, 1910.

Application filed April 1, 1909. Serial No. 487,349.

To all whom it may concern:

Be it known that I, LEWIS H. LANIER, a citizen of the United States, residing at Newport, in the county of Campbell and State of Kentucky, have invented a new and useful Improvement in Ice-Cream-Cone Ovens, of which the following is a specification.

This invention relates to an ice cream cone oven, but can also be applied to waffle irons, without any material change of construction.

The invention consists of inserting a hinged middle plate between the top and bottom plates now used, thereby doubling the capacity of the oven and permitting two of the cones to be baked with one burner and one oven where at present two burners and two ovens would be required.

In the accompanying drawings, Figure 1 is a side elevation, one of the plates being lifted and the burner casing being shown in section and broken away. Fig. 2 is a plan view showing the inner faces of the top and bottom plates and showing an edge of my middle plate. Fig. 3 is a side elevation, the middle plate being lifted in a vertical position. Fig. 4 is a section through the oven, folded, and taken on the line of the handles. Fig. 5 is a transverse section taken centrally through the oven at right angles to Fig. 4.

In these drawings 1 represents the portion of the burner casing upon which the oven is supported, 2 and 3 of the usual top and bottom plates provided with operating handles.

4, and it will be understood that as these devices are revolved in bearings provided by the burner casing 1, the terms top and bottom plates are relative terms employed only for convenience of description.

The construction above described is that of the oven now in ordinary use. In my construction however, the top and bottom plates are spaced farther apart than in the

usual construction as they do not close directly upon each other as in the common form of oven. These plates are provided with lugs 5 through which passes a suitable bolt 6 for the purpose of hinging them together. Between the plates 2 and 3 I insert a middle plate 7 provided with lugs 8 between which the lugs 5 extend, and through which the bolt 6 also passes, thus hinging all of the plates together. The middle plate 7 may be formed if desired in one piece, but

I prefer to form the middle plate of upper and lower sections *a* and *b*, the words upper and lower being also relative terms, since these plates also revolve with plates 2 and 3. The sections *a* and *b* are provided at each end with laterally extending lugs 9, the lugs of each section being arranged opposite each other and these lugs coming together space the sections *a* and *b* from each other thus forming a heating chamber 10 between the said sections. The outer faces of the sections *a* and *b* and the inner faces of plates 2 and 3 are grooved as shown at 11 to form a grid upon said faces. It will now be obvious that there is formed an oven for baking said cones between the section *a* and the plate 3 and the section *b* and the plate 2, thus enabling me to bake two cones in practically the same length of time required to bake one with the ordinary form of oven. To permit the heating of the chamber 10 the sections *a* and *b* have a greater diameter than plates 2 and 3, and the periphery of these plates are cut away upon one side as shown at 12, the said cut out portions being off-set with respect to each other. By this means the heat from the burner passes up upon one side of the bottom plate and the bottom section of the middle plate, coming into contact with the projecting marginal portion of the upper section of the middle plate, which checks further upward movement of the heat which then passes into the heating chamber 10.

It will now be obvious that while one cone is being baked between one of the outer plates and a section of the middle plate, the parts being in the position shown in Fig. 1, batter for a second cone may be placed upon the middle plate, and the top plate then closed, and the device turned and the second cone will be baked during the removal of the first, and the pouring in of another supply of batter for a third.

The operation of baking, removing and pouring in of the batter can then go on continuously and simultaneously, to a certain extent, thus greatly increasing the capacity of the oven, and at the same time decreasing the amount of fuel consumed as only one burner is in use for the double oven.

What I claim is:—

1. An ice cream cone oven comprising outer hinged plates, and a middle plate hinged between said outer plates, a heating

- chamber being formed in said middle plate, one surface of the middle plate extending in one direction beyond the body portion of the plate, and the opposite surface extending in 5 the opposite direction beyond the body portion of the said middle plate.
2. The combination with the upper and lower plates of an ice cream cone oven, of a middle plate formed of two sections spaced 10 apart and connected together.
3. In an oven of the kind described, upper and lower plates, a middle plate hinged between the upper and lower plates, one face of the middle plate coöperating with the 15 upper plate and the other face of the middle plate coöperating with the lower plate the said middle plate having a central heating chamber communicating at one side with the upper plate and upon the other side with 20 the lower plate.
4. In a device of the kind described, the combination with hinged outer plates, of a
- middle plate formed of two sections spaced apart, said sections being of a diameter greater than that of the outer plates, the said 25 sections being cut away upon one side.
5. In a device of the kind described the combination with two hinged plates having grids upon their inner faces, of a middle plate hinged between the first mentioned 30 plates, the middle plate having a central recess forming a heating chamber, the said plate having a diameter greater than the first mentioned plates, and being oppositely cut away upon its opposite sides, said cut 35 away portions affording communication from opposite sides of said middle plate to the said heating chamber, as and for the purpose set forth.

LEWIS H. LANIER.
